(57) **CLAIM**

The ornamental design for a control module for a base unit as shown and described.

DESCRIPTION

FIG. 1 is a front perspective view showing the new design for a control module for a base unit;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the designs that form no part of the claim. The long dash-short dash lines in the drawings represent a boundary of a claimed design, such as to indicate a transition from claimed subject matter to unclaimed environmental structure.

Solid lines with a comparatively lighter line weight in the drawings of the Appendix may be used to indicate surface contour of the claimed design to provide a better understanding as to the contours of the claimed design. It is to be understood that such lighter-weight solid lines are not actually part of the ornamental design (i.e., are not themselves ornamental features), but are merely provided as a visual aid to allow better understanding of the contours in the ornamental design.

(Continued)

In some computer aided drawing/renderings/figures of the application, tangent or wireframe lines (sometimes referred to as intersection lines, tangential edges or tessellation lines) are included by the software. Such lines are meant as contour lines, and are not actually part of the ornamental design (i.e., are not themselves ornamental features, such as seam lines for example), but are merely included as a visual aid to allow better understanding of the contours of the design.
